Application May 8, 1957, Serial No. 46,075

Term of patent 14 years

(Cl. D83—1)

FIG. 3

FIG. 2

FIG. 1

Figure 1 is a top plan view of a foot massager or similar article showing my new design;

Figure 2 is a rear elevational view; and

Figure 3 is a side elevational view thereof.

The design is characterized by the combination of the smoothly convexly rounded downward slope of the back portion with the forwardly convergently related sides similarly rounded from the forwardly and downwardly oblique top surface, in association with the symmetrically graduated pattern of fingerlike air slots in the hump of the back, as shown.

I claim:

The ornamental design for a foot massager, or similar article, as shown and described.
